(57) **CLAIM**

The ornamental design for a bell hanging decoration, as shown and described.

DESCRIPTION

FIG. 1 is a perspective view of a bell hanging decoration showing my new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is bottom plan view thereof.

The broken line showing of a helical shape pattern in FIG. 1 is included for the purpose of illustrating only and forms no part of the claimed design.

1 Claim, 6 Drawing Sheets

FIG. 1

FIG. 2

FIG. 3

FIG. 4

FIG. 5

FIG. 6

FIG. 7
